UNITED STATES PATENT OFFICE.

BENJAMIN D. LORING, OF PLYMOUTH, MASSACHUSETTS.

DESIGN FOR A SPOON.

SPECIFICATION forming part of Design No. 37,405, dated April 18, 1905.

Application filed March 16, 1905. Serial No. 250,478. Term of patent 7 years.

To all whom it may concern:

Be it known that I, BENJAMIN D. LORING, a citizen of the United States, and a resident of Plymouth, in the county of Plymouth and State of Massachusetts, have invented a new, original, and ornamental Design for Spoons, of which the following is a specification, reference being had to the accompanying drawing, forming part thereof.

The drawing illustrates a spoon designed in accordance with the present invention.

I claim—

The ornamental design for a spoon, as shown.

BENJAMIN D. LORING.
